INVENTOR
BY Oliver E. Noble.
Arthur C. Brown
ATTORNEY

UNITED STATES PATENT OFFICE.

OLIVER E. NOBLE, OF MANHATTAN, KANSAS.

DRAFTING DEVICE.

Application filed April 14, 1922. Serial No. 552,697.

To all whom it may concern:

Be it known that I, OLIVER E. NOBLE, a citizen of the United States, residing at Manhattan, in the county of Riley and State 5 of Kansas, have invented certain new and useful Improvements in Drafting Devices; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 This invention relates to a drafting instrument, the primary object being to provide a novel, easily operated, inexpensively constructed device capable of meeting the requirements of a draftsman and among the 20 manifold advantages of the invention is the provision of means for assisting the draftsman in making relatively large letters for drawings, maps or the like or for outlining them for sign painting, to more easily per-

25 mit the plotting of maps and transverse lines, to provide means for accurately shading cross hatching and similar operation, to assist in making ellipses, and to provide means whereby relatively large circles may 30 be accurately made.

The device in some of its operations may be used alone or it may be combined with a T-square or parallel ruler to serve as a guide.

35 The device can be associated in different ways without the T-square or parallel ruler but I prefer to utilize it in connection with a T-square because the T-square particularly lends itself for use as a complementary 40 member or guide and for that reason I have illustrated it in connection with a T-square rather than with a parallel ruler or rather than showing it to be guided by the lower edge of the drawing board.

45 In the drawings,

Fig. 1 is a plan view of the device associated with a T-square.

Fig. 2 is a sectional view on the line 2—2 of Fig. 1, showing the T-square in edge elevation.

Figs. 3 and 3^a are vertical, longitudinal, sectional views through the device and a cross sectional view through the long arm of the T-square; and

55 Fig. 4 is a plan view of a protractor.

Referring now to the drawings by numerals of reference:

1 designates a T-square of conventional form, which may serve as a guide for the device constituting the subject matter of my 60 invention. Guided upon the long blade or arm 1' of the T-square 1 is a base plate 2 having at its respective ends anti-friction rollers 3 and 4 mounted in bearings 5, 6, 7 and 8 at the ends of the slots 9 and 10.

65 The rollers are long enough to extend the width of the long blade 1' of the T-square 1 and the base plate may be guided against lateral movement by guide rollers 11 and 12 on the top edge of the blade 1' and the guide 70 roller 13 at the lower edge of the blade 1', the rollers 11, 12 and 13 being mounted below the plate 2, as will be seen in Fig. 3.

75 Cushions or rests 14, 15, 16 and 17 may be provided on the bottom face of the plate 2 and these cushions may extend slightly below the rollers 11, 12 and 13 so that when the device is used independently of the T-square, the rests will serve as supports or 80 feet for the plate 2. They are, therefore, 85 preferably constructed of resilient material, such as rubber or the like.

85 The center of the plate 2 has a heart-shaped opening 18, at the edge of which is a projection 19, having a threaded opening 20 to receive the threaded end 21 of a securing nut 22, having a peripheral flange 23 at its upper edge to engage in the shouldered portion 24 of a circumferential plate 25, which is also provided with a heart-shaped 90 opening 26, corresponding to the opening 18 to provide an opening through which the nut 22 projects so that the two plates can be secured together. It will be observed, however, that the nut 22 is threaded into the 95 plate 2 and loosely secures the plate 25 to it so that the plate 25 can turn about the axis of the nut. Therefore, the plate 2 is stationary while the plate 25 is rotatably mounted thereon.

100 About the plate 25 is a protractor ring 27, calibrated at 28 for degrees of angularity and having an indicating scale 29 for letters to show the angle at which the parts of the letters are to be formed, as will be presently 105 explained.

110 Mounted on the plate 1 and adjacent to the perimeter of the ring 27 is a locking lever 30, adapted to bind against the perimeter of the ring 27. Therefore, the ring 27 can be

held against rotation while the plate 25 can be rotated. The plate 25 carries two longitudinal guides 31 and 32 between which is a longitudinally movable, sliding frame 33. 5 The side bars 34 and 35 of the frame are connected at their respective ends by cross bars 36 and 37 and at one end of the frame 33 is a socket 38 to receive a projection 39 on a hand rest or support 40, which is provided with upstanding, curved horns or projections 41 and 42, the forward end of the table having a pin supporting arm 43 provided with a bifurcation 44 at its end to constitute a pen seat so that a pen can rest 10 in the seat 44 to draw a line when the sliding frame 33 is moved longitudinally. 15

The horns or projections 41 and 42 are to be grasped by the thumb and third and third and fourth fingers to steady the hand 20 of the operator upon the table 40 when the pen is held by him in the seat 44.

The table or hand rest 40 can be removed and in its place may be introduced the projection 45 on the protractor frame 46, the 25 protractor arm 47 being swingingly mounted in the circular seat 48 in the usual way. The protractor may be substituted for the hand rest whenever it is desired to cross hatch or section line, draw transverse lines 30 or vary the angle incident to drafting work, the table being used primarily for lettering.

The guide 32 carries a locking lever 49 to frictionally engage the side bar 35 of the frame 33 so that it may be locked in any 35 position when the protractor is used. The locking lever 49, however, will not be employed when it is desired to make the letters because in making the letters it will be necessary to slide the frame back and forth.

40 The frame may also be progressively moved in the guides 31 and 32 in section lining, cross hatching and the like, and in order to provide means for moving the straight edge uniform distances for the purpose of section lining, cross hatching, shading or the like, I provide a ratchet mechanism consisting of four bars 50, 51, 52 and 53. These are supported by the cross bars 54 and 55 and each bar has a plurality of 45 teeth 56 on its lower edge, the spaces between the teeth of each bar being different so that when the dog or detent 57 is caused to engage the teeth on one bar, the frame 33 can be moved a different distance than 50 when it is engaging the teeth on another bar.

The detent is frictionally mounted on a cross rod or support 58, journaled in bearings 59 and 60 on the lower side of the guides 31 and 32 and one end of the bar 58 is provided with a crank 61, by means of 60 which the detent can be moved out of engagement with the teeth by rocking the bar slightly.

65 The detent is slidably transversely of the

frame or longitudinally of the bar 58 so that it can be caused to align with any one of the ratchet bars 50, 51, 52 or 53, the particular bar selected determining the distance that the frame 33 will move when it is advanced one tooth with respect to the bar and gauge. For example, if close section lining is to be had, the detent will be under the bar 50. If wider cross hatching, section lining or shading is to be provided, the detent will be 70 slid along the rod 58 until it comes under the bar 51. If still wider spaces are to be provided, the teeth will be under 52 and if wider spaces are desired, under 53. The operator can push the frame forward until the tooth of the teeth clicks under the next succeeding tooth, when he will know that he has moved the frame 33 one space, and such spacing may continue until it is desired to change the size of the spacing, when 80 the detent must be shifted to another ratchet bar. 85

When it is desired to move the frame freely, the crank 61 will be used to tilt the bar 58 to move the detent out of engagement 90 with any ratchet bar so that there can be free sliding movement of the frame 33.

I have also provided means for assisting in constructing ellipses and in order to provide an ellipsograph as part of the invention, I extend from one edge of the plate 2 a guide 95 consisting of the two bars 62 and 63, in which is a sliding plate 64. The sliding plate carries a rod clip 65, slidably mounted on a longitudinal rod 66 pivoted at 67 to a transverse bar 68 adjustable on the side bars 34 and 35. The bar 68 has depending ends which lap over the edges of the side bars 34 and 35 in the form of an inverted U and in one of these bars is a set screw 69, (see Fig. 1) which can be manipulated to bind the bar 100 on the sliding frame 33 at any position dependent upon the size of the ellipse. The clip 65 is also provided with a set screw 70, whereby the clip can be adjustably secured 105 on the rod 66. Therefore, when it is desired to form an ellipse, the size of the ellipse will be determined by the adjustment of the clip 68 on the rod 66; then the 110 end of the pen or pencil will be introduced in the seat 44 and the plate 64 swung about the axis of the nut 22, the bar 68 being fixed to the frame 33 and the clip 65 being fixed to the rod 66 so that the rod 66 will act as a link between the pivoted clip 65 and its 115 pivotal connection with the bar 68.

It will be apparent that in view of the fact that if the slide 64 is held rigid in the guide, there will be a sliding movement imparted to the frame 33 as the plate 25 rotates about the axis of the nut 22. Therefore, the point 44 will scribe an ellipse, the size of the ellipse being determined by the distance between the clip 65 and the bar 68. 125

130 The slide 64 can be secured against move-

ment or held in fixed adjustment by a latch lever 71, carried by the side bar 63. The extension frame consisting of the side bars 62 and 63 can be removed and the bar 68 5 may also be taken off so that the device can be operated without the ellipsograph if desired.

When it is desired to letter, the ellipsograph can be removed from the plate 2 and 10 the instrument may be placed on the T-square, as shown, with the T-square preferably secured to the work by a thumb tack or other suitable means. The locking lever 49 is then in released position and the indicator point 72 can be moved around to 15 the letter on the scale 29 which it is desired to make, which will indicate the proper slant to be followed, whether vertical, inclined or horizontal, and the proper angle 20 at which these strokes shall be made.

It is understood that the horns 41 and 42 will be grasped by the hand of the operator while the pen held in his hand will have its 25 point resting in the crotch of bifurcated portion 44.

When it is desired to use a protractor table, all the hand rests will be removed and in lieu thereof will be placed the protractor, as above described. When it is desired 30 to use the device as an ellipsograph, the ellipsograph attachment can be introduced into the frame 33 and the operation carried out as previously explained.

It will be apparent from the foregoing 35 that the device is capable of a multitude of uses, that it is easy to operate, that it can be conveniently associated with an ordinary T-square or other appropriate guiding mechanism, and that it will be inexpensive 40 to manufacture.

What I claim and desire to secure by Letters-Patent is:

1. A device of the class described comprising a base, a rotatable plate on the base, 45 a slidable frame carried by the rotatable plate, a slidable tool carrier on the slid- able frame, means for fixing the rotatable plate rigid with respect to the base, and means for fixing the slidable frame rigid 50 with respect to its plate.

2. A device of the class described comprising a traveling base, a rotatable plate mounted on the base, a ring mounted about the plate, means for fixing the ring rigid 55 with respect to the base, a slidable frame carried by the rotatable plate, means for fixing the slidable frame with respect to the plate, means for removably securing a tool to one end of the plate, a plurality of ratchet bars longitudinally of the frame and having teeth to provide separate spacings for each bar, a detent carried by the plate 60 and adapted to engage the teeth on the bars, the teeth being shiftable to align with first

one bar and then the other, and means for 65 moving the detent out of engagement with the teeth on the bars.

3. A device of the class described comprising a main plate, a rotatable plate carried thereby, a ring scale about the second 70 named plate and having movement both independent thereof and therewith, a longitudinally movable frame on the rotatable plate, a tool carrier at one end of the frame, a rigid projection carried by the main plate, 75 a bar on the frame, a rod carried by the bar, and means for pivotally connecting the bar to the rigid projection.

4. A device of the class described comprising a main plate, a rotatable plate carried thereby, a longitudinally movable frame carried by the plate, a tool at one end of the frame, a rigid projection carried by the main plate, a slide supported by the projection, 80 a clip on the slide, a bar adjustably mounted on the frame, and a rod adjustably connected to the clip.

5. A device of the class described comprising a plate, guide-engaging rollers carried by the plate, a rotatable plate carried by 90 the main plate, a scale ring about the rotatable plate, parallel guides on the rotatable plate, a frame mounted in said guides, rack bars carried by the frame, a detent carried by the rotatable plate for engagement 95 with the teeth on the rack bars, and means for securing a tool to one end of the frame.

6. A device of the class described comprising a main plate, a rotatable plate carried thereby, a shiftable scale about the rotatable plate, means for fixing the scale in adjusted position, a longitudinally movable frame carried by the rotatable plate, 100 and means for securing a tool to one end of the frame.

7. A device of the class described comprising a main plate, a rotatable plate carried thereby, a shiftable scale about the rotatable plate, means for fixing the scale in 110 adjusted position, a longitudinally movable frame carried by the rotatable plate, a hand rest at one end of the frame, finger-engaging projections carried by the hand rest, and a pen support carried by the hand rest. 115

8. A device of the class described comprising a main plate, a rotatable plate carried thereby, a longitudinally movable frame carried by the rotatable plate and adapted to rotate therewith, a connection 120 carried by the main plate and independently of the rotatable plate, means for linking the slidable frame with the connection, and a pen rest carried by one end of the frame.

In testimony whereof I affix my signature. 125

OLIVER E. NOBLE.
